UNITED STATES PATENT OFFICE.

ERNEST B. LYDICK, OF PITTSBURGH, PENNSYLVANIA.

DESIGN FOR A FRUIT-KNIFE.

44,211.

Specification for Design.

Patented June 17, 1913.

Application filed April 26, 1913. Serial No. 763,906. Term of patent 14 years.

To all whom it may concern:

Be it known that I, ERNEST B. LYDICK, a citizen of the United States, residing at Pittsburgh, in the county of Allegheny and State of Pennsylvania, have invented a new, original, and ornamental Design for Fruit-Knives, of which the following is a specification, reference being had to the accompanying drawings, forming part thereof, and in which the figure is a side view of the knife, showing my new design.

I claim:

The ornamental design for a fruit knife, as shown.

ERNEST B. LYDICK.
